DEVICE FOR VENTILATING WAVE-GUIDE SYSTEMS

Hans Allaries, Eindhoven, Netherlands, and Arnold Edmond Marie Calon, Bobigny, France, assignors to North American Philips Company, Inc., New York, N.Y., a corporation of Delaware

Application April 1, 1957, Serial No. 649,733

Claims priority, application Netherlands April 19, 1956

2 Claims. (Cl. 333—98)

This invention relates to devices for ventilating wave-guide systems.

For wave-guide systems in permanent arrangements such as, for example, in radar installations or beam transmitter stations, it is frequently necessary to take steps in order that dried and/or heated air or a neutral gas, for example nitrogen, may be blown into the wave-guide system to avoid corrosion and condensation of water vapour. The gas container or the drying and/or heating installations of the air to be blown into the system must be connected somewhere at the beginning or the end of the wave-guide system. The couplings concerned are required to affect the electric field configurations as little as possible. This may be achieved in known manner by choosing the coupling holes or slots to be comparatively small with respect to the wavelength of the waves in the wave-guide. For very high frequencies such, for example, as correspond to millimetre waves, the coupling holes must, however, be so small as to constitute a considerable resistance to flow, so that insufficient gas or air can flow through the wave-guide.

In the device according to the invention for ventilating wave-guide systems, a directional coupling known per se is provided, at least one coupling opening being provided in the adjacent side-walls of the wave guides such that wave energy supplied via a given extremity of one wave guide is discharged completely through a given extremity of the other wave guide, and conversely. Furthermore, the other extremity of one wave guide is coupled to means for maintaining a gas flow in the wave-guide system whereas the other end of the other wave-guide is shut off in a gas-tight manner.

In order that the invention may be readily carried into effect, one embodiment will now be described, by way of example, with reference to the accompanying drawing showing a known directional coupling with two wave guides G1 and G2. A transmitter is connected, for example, to the left-hand end A of wave-guide G1 and an antenna is connected to the right-hand end B of wave-guide G2. The common side-wall of the wave-guides G1 and G2 has provided in it a coupling opening KG, which is so proportioned that wave energy supplied via the end A is transferred completely via the coupling opening KG to the wave guide G2 and may be discharged via the end B. The coupling factor of such a directional coupling may be equal to unity in a comparatively broad frequency range, for example a relative variation of 15%, that is to say that substantially no energy is transferred to the arms C and D of the direc-

2

tional coupling and these arms thus are electrically neutral. The arm C is connected to a device for maintaining a gas flow in the wave-guide system, for example a gas container or an air pump, if desired further means being provided for drying and/or heating the blow air. The arm D of wave guide G1 is shut off in a gas-tight manner by means of a wall or piston Z, which wall also prevents escapement of any high-frequency energy via the arm D. The blow air is thus led via the arm B to the aerial and via the coupling opening KG and the arm A of wave-guide G1 to the transmitter. As a matter of fact, the coupling opening KG has only a very small resistance with respect to the air flow. In order to prevent wave energy from escaping via the arm C or leaking in via the pump, it may be desirable for the dimensions of the pipe concerned to be chosen such that travelling waves cannot occur therein, which on the other hand has the disadvantage that the resistance to flow is increased. Consequently, the wave pipe C is preferably not narrowed, but a thin metallic partition S is arranged at the centre thereof, as shown in the drawing.

What is claimed is:

1. A device for ventilating a waveguide system, comprising first and second hollow pipe waveguides, means for supplying electrical wave energy into an end of said first waveguide, means providing at least one hollow electrical coupling from a side of said first waveguide to a side of said second waveguide thereby providing a directional coupling whereby said wave energy is discharged at an end of said second waveguide, means connected to the remaining end of said second waveguide for inducing gas into said system, means closing the remaining end of said first waveguide in a gas-tight manner, and means preventing escape of said wave energy through said remaining end of said second waveguide comprising a metallic partition centrally disposed in said remaining end of said second waveguide and extending longitudinally therewith.
2. A device for ventilating a waveguide system, comprising first and second hollow pipe waveguides positioned side-by-side along at least a portion of the lengths thereof thereby providing a common sidewall, means for supplying electrical wave energy into an end of said first waveguide, means connected to a corresponding end of said second waveguide for inducing gas into said system, said common sidewall containing at least one aperture thereby providing a directional coupling whereby said wave energy is discharged at the remaining end of said second waveguide, means closing the remaining end of said first waveguide in a gas-tight manner, and means preventing escape of said wave energy through said corresponding end of said second waveguide comprising a metallic partition centrally disposed in said corresponding end of said second waveguide and extending longitudinally therewith.
